(57) **CLAIM**

The ornamental design for a travel tumbler, as shown and described.

DESCRIPTION

FIG. 1 is a front and top perspective view of a travel tumbler, showing my design.

FIG. 2 is a rear and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view of the travel tumbler wherein a suction nozzle of the travel tumbler is open.

The broken lines in the drawings depict portions of the travel tumbler that form no part of the claimed design.
